BOTTLE DRIER

Warren M. Sample, Muncie, Ind.

Application October 29, 1936, Serial No. 108,280

11 Claims.

(Cl. 34—1)

This invention relates to certain new and useful improvements in bottle driers.

Bottled drinks of various characters are usually chilled in ice receptacles and the bottles are immersed in iced water with the result that great inconvenience is experienced in the handling of the bottles for drinking purposes. It is therefore the primary object of this invention to provide a drier for such bottles wherein practically all of the water is removed from the sides and bottom of the bottle so that the same is delivered to a customer in a substantially dry condition for more convenience in drinking the contents of the bottle directly from the bottle or in pouring the contents into a glass.

Another object of the invention is to provide a bottle drier of the foregoing character embodying a casing having an opening in the top wall thereof with manually operable clamp members within the casing that are lined with absorbent material and adapted to be grippingly engaged with a bottle inserted into the casing at the top opening thereof for the removal of water from the outer sides of the bottle, the water draining from the absorbent members into the bottom of the casing for discharge therefrom to a convenient point.

With the above and other objects in view that will become apparent as the nature of the invention is better understood, the same consists in the novel form, combination and arrangement of parts hereinafter more fully described, shown in the accompanying drawings and claimed.

In the drawings:—

35 Figure 1 is a perspective view of a bottle drier constructed in accordance with the present invention and illustrating the casing with an opening in the top wall thereof for the introduction of the bottle to be dried;

40 Figure 2 is a cross-sectional view taken on line 2—2 of Figure 1, illustrating a bottle by dotted lines within the drying clamp members and with one of the clamp members illustrated in its released position by dotted lines;

45 Figure 3 is a cross-sectional view taken on line 3—3 of Figure 2;

Figure 4 is a horizontal sectional view taken on line 4—4 of Figure 2, showing one drying clamp member shiftably mounted relative to the other rigid drying clamp member;

Figure 5 is a perspective view of the bottle drying element removed from the enclosing casing with the shiftable drying clamp member in its releasing or open position;

55 Figure 6 is a vertical sectional view of another

form of bottle drying device wherein a drying pad constitutes a bottom support for the bottle, the shiftable drying clamp member being illustrated in its released or open position by dotted lines;

5 Figure 7 is a vertical sectional view taken on line 7—7 of Figure 6; and

Figure 8 is a horizontal sectional view taken on line 8—8 of Figure 6.

Referring more in detail to the accompanying drawings and particularly to Figures 1 to 5, there is illustrated a bottle drier comprising a bottom pan 10 upon which a casing is mounted that includes side walls 11 and a removable cover 12 retained in position on the side walls 11 by the screw devices 13 shown in Figures 1 and 3, the cover 12 of the casing being provided with a bottle receiving opening 14.

The bottle drying devices are located within the tank and casing and include a base plate 15 having openings 16 therein as shown in Figure 5 to facilitate the anchoring of the base plate on blocks or feet 17 that space the base plate from the bottom wall of the tank 10 as shown in Figures 2 and 3, fastening screws 18 or the like passing through the openings 16 in the base plate and feet 17 to enter a counter, shelf or the like 19 for the support of the device. The bottle drying devices per se include a cylindrical member longitudinally slit to provide clamp sections 20 and 21, the section 20 extending through an arc greater than 180° as illustrated in Figure 4 to maintain the bottle in an upright position when the clamp members 20 and 21 of the drier are separated. An absorbent or like lining 22 is provided for the drier sections 20 and 21 and may be anchored to the drier sections by a lacing 23 for holding the same in position. A block 24 rises from the base plate 15 adjacent one end thereof and rigidly supports the clamping 40 drier section 20, the drier section 21 being shiftable relative to the section 20.

To effect movement of the shiftable drier section 21, a shaft 25 is journaled in the block 24 and projects from each end of the block into the casing 11, one end of the shaft 25 projecting exteriorly of the casing for the attachment thereto of a hand lever 26. A rocker arm 27 is fixed to each end of the shaft 25 adjacent the block 24 and within the casing 11 and each rocker arm 27 has a link connection 28 with the shiftable clamping drier section 21, the links being respectively pivoted as at 29 to the rocker arms 27 and also pivoted as at 30 to the shiftable drier section 21. An abutment block 31 55

5 rises from the base plate 15 in spaced relation to the shiftable clamping drier section 21 and in the path of opening movement of said section to cause the latter to tilt and assume the dotted line position illustrated in Figure 2 whereby the bottle B illustrated by dotted lines in Figure 2 may be more readily removed from the drying device. A valve 32 is associated with the tank 10 for the removal of water therefrom.

10 Numerous roadside restaurants and gasolene service stations sell bottled drinks and the bottles are chilled by placement in iced water and the serving of the wet bottles to customers presents many inconveniences in the handling thereof.

15 The device disclosed in this application is intended for association with receptacles containing such chilled bottled liquid so that when a bottle is removed from the iced water in a wet condition, the same is introduced through the top opening 14 in the casing 11 for reception in the clamping drier sections 20 and 21, the open position of the drier sections including the shifting of the section 21 to the dotted line position shown in Figure 2. When a bottle B is placed 20 in the casing, the lever 26 is manually operated to move the clamping drier section 21 into mating engagement with the stationary drier section 20, the absorbent lining 22 on the drier sections removing substantially all water from the exterior 25 surface of the bottle so that the same may be delivered to a customer in a practically dry condition. The water draining from the bottle and also from the absorbent lining collects in the lower tank 10 and may be discharged at will to the valved drain 32. The clamping drier section 20 extends through an arc in excess of 180° and acts to retain the bottle B in an upright position after the drier section 21 has moved away from the stationary section 20 to facilitate removal 30 of the bottle from the casing, the abutment block 31 causing the shiftable clamping drier section 21 to tilt and in no manner hinder removal of the bottle from the casing.

35 In the form of invention illustrated in Figures 6 to 8, a drying device is associated with the bottom of the bottle, the general construction of the casing and operating devices being substantially the same as the form of invention illustrated in Figures 1 to 5, a pair of bearing blocks 24a being provided for anchoring the rigid clamping drier section 20a and providing bearings for the shaft 25a. Rock arms 27a are carried by the shaft 25a and have link connections 28a with the shiftable clamping drier section 21a. An arm 33 is mounted upon the shaft 25a intermediate the bearing blocks 24a through the medium of a bearing collar 34 and said shaft has limited movements independently of said arm and bearing collar provided by a screw pin 35 carried by the shaft 25a and projecting through the slotted opening 36 in the bearing collar. The arm 33 projects through an opening 37 adjacent the lower end of the clamping drier section 20a and carries at its forward end a disk disposed at the lower end of the cylindrical drier and upon which disk an absorbent pad 39 is secured. The shaft 25a is operated by the hand lever 26a, the initial movement of the parts when the shiftable section 21a is in the dotted line position shown in Figure 6 being to move said shiftable section toward the stationary section 20a until the screw pin 35 reaches one end of the slot 36 in the bearing collar 34 and at which time the disk 38 upon the end of the arm 33 and the absorbent pad 39 40 will be moved upwardly a distance sufficient to

compress the absorbent pad 39 for the absorption from water clinging to the bottom of the bottle. An opening 40 is provided in the base plate 15a for drainage purposes and also for clearance for movement of the free end of the arm 33.

5 From the above detailed description of the invention, it is believed that the construction and operation thereof will at once be apparent and while there are herein shown and described the preferred embodiments of the invention, it is nevertheless to be understood that minor changes may be made therein without departing from the spirit and scope of the invention as claimed.

I claim:—

1. In a bottle drier, a pair of clamping drier sections, one of said sections being movable relative to the other section, means for shifting the movable section, the combined sections being of cylindrical form and one of said sections being of an arc greater than 180°.

15 2. In a bottle drier, a pair of clamping drier sections, one of said sections being stationary and the other section being movable relative thereto, means for shifting the movable section, and a bottom drier section at the lower end of the clamping drier sections adapted to be moved relative to both sections when the sections are moved into clamping engagement.

25 3. In a bottle drier, a pair of clamping drier sections, one of said sections being movable relative to the other section, means for shifting the movable section, the combined sections being of cylindrical form and one of said sections being of an arc greater than 180°, and a bottom drier section at the lower end of the clamping drier sections.

30 4. In a bottle drier, a pair of clamping drier sections, one of said sections being stationary and the other section being movable relative thereto, means for shifting the movable section, a bottom drier section at the lower end of the clamping drier sections, and operatively engaged with the shifting means for the movable clamping section for slight movement upwardly relative to the clamping sections when said sections are moved into clamping engagement.

35 5. In a bottle drier, a pair of clamping drier sections, one of said sections being movable relative to the other section, means for shifting the movable section, the combined sections being of cylindrical form and one of said sections being of an arc greater than 180°, a bottom drier section at the lower end of the clamping drier sections, and operatively engaged with the shifting means for the movable clamping section for slight movement upwardly relative to the clamping sections.

40 6. In a bottle drier of the character described, a casing having a drain tank at its lower end and a cover with a bottle receiving opening therein, a perpendicular cylindrical bottle drier within the casing beneath the top opening, said drier being longitudinally split to provide two sections, one of which is rigidly mounted in the casing and the other section being relatively shiftable, a manually operable shaft having rocker arm and link connections with the movable section, and means to effect tilting movement of the movable section when moved away from the stationary section.

45 7. In a bottle drier of the character described, a casing having a drain tank at its lower end and a cover with a bottle receiving opening therein, a perpendicular cylindrical bottle drier within the casing beneath the top opening, said drier

- being longitudinally split to provide two sections, one of which is rigidly mounted in the casing and the other section being relatively shiftable, a manually operable shaft having rocker arm and link connections with the movable section, means to effect tilting movement of the movable section when moved away from the stationary section, and a bottom drier section at the lower end of the aforesaid drier sections and operatively engaged with said shaft to be slightly moved upwardly into intimate contact with the bottom of a bottle for the more effective removal of water from the bottom of the bottle. 5
8. In a bottle drier, a pair of clamping drier sections, one of said sections being movable relative to the other section, means for shifting the movable section, a bottom drier section at the lower end of the clamping drier sections, operatively engaged with the shifting means for the 10 movable clamping section for slight movement upwardly relative to the clamping sections, the connection of the bottom drier with the operating means being such that the movable section of the drier sections moves in advance of the movement of the bottom drier. 15
9. In a bottle drier, a pair of clamping drier sections, one of said sections being movable relative to the other section, means for shifting the movable section, the combined sections being of 20 cylindrical form and one of said sections being of an arc greater than 180°, a bottom drier section at the lower end of the clamping drier sections, and operatively engaged with the shifting means for the movable clamping section for slight movement upwardly relative to the clamping sections, the connection of the bottom drier with the operating means being such that the movable section of the drier sections moves in advance of the movement of the bottom drier. 25
10. In a bottle drier of the character described, a casing having a drain tank at its lower end and a cover with a bottle receiving opening therein, a perpendicular cylindrical bottle drier within the casing beneath the top opening, said drier being longitudinally split to provide two sections, one of which is rigidly mounted in the casing and the other section being relatively shiftable, a manually operable shaft having rocker arm and link connections with the movable section, means to effect tilting movement of the movable section when moved away from the stationary section, the connection of the bottom drier with the operating means being such that the movable section of the drier sections moves in advance of the movement of the bottom drier. 30
11. In a bottle drier of the character described, a casing having a drain tank at its lower end and a cover with a bottle receiving opening therein, a perpendicular cylindrical bottle drier within the casing beneath the top opening, said drier being longitudinally split to provide two sections, one of which is rigidly mounted in the casing and the other section being relatively shiftable, a manually operable shaft having rocker arm and link connections with the movable section, means to effect tilting movement of the movable section when moved away from the stationary section, a bottom drier section at the lower end of the aforesaid drier sections and operatively engaged with said shaft to be slightly moved upwardly into intimate contact with the bottom of a bottle for the more effective removal of water from the bottom of the bottle, the connection of the bottom drier with the operating means being such that the movable section of the drier sections moves in advance of the movement of the bottom drier. 35
